SELF-LOCKING KEY RING

James F. Hetz, Cincinnati, Ohio

Application July 16, 1952, Serial No. 299,097

4 Claims. (Cl. 70—459)

1

My invention relates to the provision of an improved self-locking key ring.

It is an object of my invention to provide a self-locking key ring which may be manufactured cheaply and which will be of durable construction.

It is a further object of my invention to provide a self-locking key ring having means to prevent the key ring from accidentally being pulled apart.

Another object of my invention is to provide a key ring in which there are means provided to insure against the accidental displacement of keys therefrom.

A further object of my invention is to provide a self-locking key ring which is adapted to be used in connection with the modern type of key now commonly in use.

These and other objects and advantages of my invention will become apparent to those skilled in the art during the course of the following description and from reference to the accompanying drawings in which like numerals are employed to designate like parts throughout the same and in which:

Figure 1 is a side elevation showing my novel self-locking key ring.

Figure 2 is an end elevation.

Figure 3 is a side elevation with parts removed.

Figure 4 is a side elevation of one of the elements employed in the key ring of this invention.

Figure 5 is a greatly enlarged sectional view on the line 5—5 of Figure 4.

Figure 6 is a greatly enlarged sectional view on the line 6—6 of Figure 1 and

Figure 7 is a view similar to that of Figure 1 but showing the key ring in that position when a key is shown in process of being either placed on or off the key ring.

Referring now to the drawings it will be observed that my novel self-locking key ring comprises a main body plate including a smaller diameter open jawed end and a larger diameter loop. The smaller open jawed end comprises the jaw members 10 and 11 while the larger diameter loop is indicated at 12. Also included in my novel key ring are a pair of notched discs 13 which are fastened one on either side of the key ring by means of a rivet 14 passed through the disc and a center hole 15 provided in the main body plate of which the jaw member 11 is a part. Each disc 13 is notched as at 16.

The key ring is assembled by placing a notched disc 13 on either side of the open jawed end of the key ring main body plate. These discs are 55

2

assembled in such a manner as to permit free rotation thereof, the rivet 14 at the same time holding them in fairly snug engagement with the body of the ring. It is pointed out that the 5 exterior edges of the members 10 and 11 form portions 17 and 18 respectively of a circle having its center at 15. The main ring portion 12 corresponds generally to a circle having a center at 19. It is a specific feature of my invention 10 that a line passed through the center points 15 and 19 will intersect the thin jaw 10 of the open jawed end of the key ring so as to provide a substantial portion 20 extending beyond the point of intersection just described. This is a material aid to imparting rigidity to the ring structure.

It should be noted that the open end jaw members 10 and 11 are so arranged as to provide a channel 21 of sufficient width to accept keys of 20 modern design.

The special construction of each of the discs 13 forms a distinct feature of my invention. Such construction is best shown in Figures 5 and 6. In these figures it will be seen that each 25 of the discs is essentially a flat member having its outer edges turned as indicated at 22. Each of the discs 13 is so constructed that when it is centered in place on the ring by means of the rivet 14 the outer edges 22 will engage about the outer edges 17 and 18 of the open jawed end members 10 and 11 respectively.

As best seen in Figure 6, it will be observed that where the discs 13 come into contact with the member 12, the turned-in edges 22 must ride 35 on the exterior surfaces of such member 12. This slightly cocks each of the discs in the direction of the member 10 with the result that the gripping function of the turned-in edges 22 about this member 10 is enhanced. The purpose of so 40 constructing the disc 22 is to insure against the thin, unsupported jaw member 10 being accidentally pulled away from the jaw member 11. Were it not for this construction and were the member 10 somehow pulled apart from the member 11 it will be apparent that keys on the loop 12 might more easily spill therefrom. In this connection it should be noted that the added portion 20 of the member 10 requires a greater distortion of such member before the danger 45 point is reached.

In use the discs 13 are so positioned that each of the U-shaped notches 16 is aligned with one edge adjacent the extreme end 20 of the thin jaw member 10. The key 23 is then advanced to 50 the larger diameter loop 12 of the key ring

main body plate. As the key is so advanced the notched disc on either side of the ring rotates freely until the key reaches the loop 12. After the key is thus advanced to the center of the loop 12 the discs 13 may then be rotated somewhat further so as to properly seal the entrance channel 21. To this end a further feature of my invention lies in the operation of the turned-in edges 22 in conjunction with the notches 16. Thus, after a key is placed on the loop 12 and the discs 13 rotated a bit further, it will be apparent that the notch portion 16 may engage about the loop 12 in the area generally indicated at 24 in Figure 7. The turned-in edges 22 which, of course, are broken in the region of the notch 16 forms an abutment which serves to keep the notches 16 about either side of the loop 12 in the area 24 until such time as the user forces the discs to the exit position. Even should the notches 16 become disengaged from the portion 24 accidentally, it is still unlikely that both of the discs would take such position that the notches 16 would register with each other so as to permit the key to leave the ring accidentally.

In operation then, the parts are assembled in such a manner as to permit free rotation of the notched discs 13, which when aligned with the opening provided by the jaw ends 10 and 11 of the key ring main body plate permit admission of a key. The key is then advanced to a larger diameter loop end 12 of the key ring main body plate. As a key is advanced to this larger diameter loop end 12 the notched discs 13 on either side of the key ring plate rotate freely. After the key is permitted to advance to the center of the loop 12, the discs are rotated an additional amount so as to seal the entrance channel opening 21. Furthermore, the notched portions 16 may engage about the portions 24 so as to hold the discs 13 in such position as to prevent a key from leaving the main ring portion 12. This locks the key in the larger diameter loop end 12 so that it cannot be removed, other than accidentally (which is very unlikely as above pointed out) until the notched discs 13 are rotated and re-aligned in exact position with the channel opening 21 in the open jawed end of the key ring main body plate.

It is emphasized that the thin jaw 10 of the opened jawed end of the key ring main body plate must extend substantially past the center line of the ring, this extension being indicated at 26. This is the preferred arrangement.

In addition it is further emphasized that the discs 13 must be of sufficient size that the turned-in edge 22 will engage about the exterior edges 17 and 18 of the open end jaw members 10 and 11 respectively. This further adds to the rigidity of the device by preventing the member 10 from being pulled away from the member 11. These turned-in edges 22 exert a gripping pressure on the outside edges 17 and 18. By locking the thin jaw 10 of the key ring main body plate in this manner, the possibility of spilling keys from the larger diameter loop end 12 is eliminated.

It is to be understood that although I have

described my invention as embodying certain structures and particular arrangement, I do not intend to be limited by such structures and arrangement except insofar as they are specifically set forth in the sub-joined claims. It will be further understood that modifications and changes in my invention may be made without departing from the scope and spirit thereof.

Having thus described my invention what I claim as new and what I desire to protect by United States Letters Patent is:

- 10 1. A self-locking key ring comprising a main body plate having a large loop at one end and a smaller open jawed arrangement at the other end, said open jawed arrangement including a relatively thin member and a relatively thick member, said thin and thick members defining a passageway therebetween communicating with said loop, and a pair of discs rotatably fastened one at either side of said main body plate, each of said discs being notched a width generally corresponding to the width of said passageway, each of said discs having turned-in edges engaging about the outer edges of said thin and thick members.
- 15 2. The device of claim 1 in which said discs are fastened to said plate by means engaging said discs and said relatively thick member.
- 20 3. The device of claim 2 in which said passageway defines a tortuous path about said engaging means and in which said thin member has a free end extending substantially past the center line of the plate passing through said engaging means.
- 25 4. A self-locking key ring comprising a substantially flat plate having a large loop the exterior edges of which generally correspond to a circle, the ends of said loop being return bent and configured to have exterior edges corresponding to a smaller circle, one of said ends terminating in a member corresponding in cross section to that forming said large loop and the other of said ends terminating in a member considerably thicker, said first mentioned member and said thicker member defining a channel communicating with said loop, and a pair of discs fastened to said thicker member on either side of said plate, said discs having turned-in edges adapted to engage about those exterior edges which correspond to the smaller circle and to ride on said large loop in the area of said return bend, said discs having notches of a width corresponding to that of said channel.
